UNITED STATES PATENT OFFICE.

RUSKIN WILLIAMS, OF WOODSTOCK, NEW YORK.

DESIGN FOR A BENCH.

Application filed October 27, 1927. Serial No. 23,909. Term of patent 7 years.

To all whom it may concern:

Be it known that I, RUSKIN WILLIAMS, a citizen of the United States, residing at Woodstock, in the county of Ulster and State of New York, have invented a new, original, and ornamental Design for a Bench, of which the following is a specification, reference being had to the accompanying drawing, forming part thereof.

I claim:

The ornamental design for a bench, as shown.

RUSKIN WILLIAMS.
